United States Patent Office

Des. 221,039
Patented June 29, 1971

221,039

UMBRELLA FRAME

Richard Zimmermann, Leichlingen, Rhineland, Germany,
assignor to W. Bauermann & Soehne GmbH, Hilden,
Rhineland, Germany

Filed Mar. 3, 1970, Ser. No. 21,723

Claims priority, application Germany Sept. 4, 1969

Term of patent 14 years

Int. Cl. D3—03

U.S. Cl. D88—3

FIG. 1

FIG. 1 is a perspective view of an umbrella frame showing my new design;

FIG. 2 is a fragmentary side elevational view of the umbrella frame;

FIG. 3 is an enlarged fragmentary perspective view of the umbrella frame top;

FIG. 4 is an enlarged fragmentary perspective view of the umbrella frame slider; and

FIG. 5 is an enlarged fragmentary perspective view of the umbrella frame handle.

I claim:

The ornamental design for an umbrella frame, substantially as shown.
